UNITED STATES PATENT OFFICE.

GEORGE D. HOWE, OF DAVISON, MICHIGAN.

INTERNAL-COMBUSTION ENGINE.

1,384,133.

Specification of Letters Patent. Patented July 12, 1921.

Application filed January 27, 1920. Serial No. 354,496.

To all whom it may concern:

- Be it known that I, GEORGE D. HOWE, a citizen of the United States of America, residing at Davison, in the county of Genesee and State of Michigan, have invented certain new and useful Improvements in Internal-Combustion Engines, of which the following is a specification, reference being had therein to the accompanying drawings.
- 10 This invention relates to multi-cylinder internal combustion engines and has special reference to that type of engine having pistons therein articulated with a crank shaft for driving said shaft when explosive mixtures are detonated in the cylinders of the engine above the pistons. Such an engine ordinarily has intake and exhaust valves controlling the admission of gas or an explosive mixture to the cylinders and the exhaust of burned gases therefrom, said intake and exhaust valves being operated in timed relation from a cam shaft suitably driven by the crank shaft of the engine. The intake and exhaust thereof necessitates the use of 20 conduits or manifolds for conducting the gases to and from the engine, one of the conduits being known as the exhaust manifold and the other as an intake manifold, which is generally connected to a carbureter or 25 source of fuel for the intake.
- My invention, in its broadest aspects, involves the circulation of an explosive mixture through the cylinders of the engine so that the explosive mixture may be heated, 30 prior to being detonated, and placed in a better condition for combustion. To do this certain changes or additions are necessary to the engine, and each change or addition may be characterized in the following particulars.
- 40 First, the engine cylinders and the connecting rods may be re-proportioned. If the diameters of the cylinders are increased the connecting rods are maintained the usual length and stroke, but if the cylinders are 45 increased in their longitudinal dimensions so that the engine cylinders will be of greater length than ordinary cylinders, then the connecting rods are proportionately increased so that a greater piston stroke is attained which reduces to a minimum piston 50 slap, vibration, and insures quieter and smoother running of the engine. Another advantage gained is that of providing a comparatively longer compression stroke for the 55 piston, the first portion of the long compression stroke permitting of a portion of the
- explosive mixture within the cylinder being transferred, as will hereinafter appear, and the remaining portion of the stroke actually compressing, and permitting of a 60 greater amount of energy or work being derived from detonated and expanding gases in the cylinder by the long return or work stroke of the piston. It is a well known fact that the exhaust from the average explosive engine 65 indicates that the released burned gases are not at atmospheric pressure and in many instances are at high pressure when released. By providing a greater work stroke for the piston it is possible to utilize some of the 70 pressure heretofore exhausted, and consequently greater efficiency may be expected from an engine in accordance with this invention.
- Second, I provide the engine with what 75 may be termed "excess discharge valves" which are located in proximity to the intake and exhaust valves of the engine and operated from the cam shaft, the discharge valves being timed so as to open while the 80 intake and exhaust valves of the cylinder are closed and during approximately one-third of the compression stroke of the piston, bearing in mind that the cylinder has been made a greater diameter or a greater length than 85 an ordinary cylinder and the piston stroke increased. It is now obvious that with the discharge valve open that a third of the volume of explosive gas or fuel within the cylinder may be displaced. But, while the 90 excess quantity of gas has been passed through the cylinder it has been heated by the walls thereof and it is this warm mixture which I conduct to the main supply of fuel so that it will commingle therewith and 95 provide a better combustion. To do this, it is necessary to provide an auxiliary manifold communicating with the excess discharge valve so that the excess explosive mixture may be collected and conducted to 100 the supply of fuel. The auxiliary manifold may be connected to the main manifold, adjacent the carbureter of the engine or connected to the air intake connection of the carbureter, just so that the warmed explosive mixture will commingle with the initial charge to a cylinder, raise its temperature and place it in a better condition. In 105 some instances, the intake, exhaust and auxiliary manifolds may be cast *en bloc*.
- Other advantages and benefits to be derived from my invention will more readily

appear as the nature of the invention is better understood, and reference will now be had to the drawings, wherein—

Figure 1 is a plan of a multi-cylinder internal combustion engine in accordance with my invention, showing a cylinder head removed;

Fig. 2 is a side elevation of the engine, partly broken away and partly in section, 10 and

Fig. 3 is a vertical sectional view taken on the line III—III of Fig. 2.

First considering the usual construction of the engine, there is a crank case 1 containing a crank shaft 2 and on the crank case is mounted a cylinder block 3 having water jackets 4 and cylinders 5, the cylinders 5 containing pistons 6 operatively connected to cranks 6^a of the crank shaft 2 by 20 connecting rods 7.

On the cylinder block 3 is a head 8 providing chambers 9 for intake valves 10 and exhaust valves 11, said valves having rods 12 adapted to be raised through the medium 25 of a cam shaft 13 operated from the crank shaft 2, the valves 10 and 11 being closed in the usual manner. Below the valves 10 and 11 are intake chambers 14 and exhaust chambers 15, the former communicating 30 with a main intake manifold 16 and the latter communicating with an exhaust manifold 17, said manifolds being supported in the usual manner relative to the cylinder block.

At the side of the engine is a conventional form of carbureter 18 having an air intake connection 19 and an outlet connection opening into the main intake manifold 16 of the engine. All of the elements thus far described are common in many types of 40 internal combustion engines, and my present improvement resides in the charge rejecting means. As set forth in the beginning, I may make the cylinders 5 and connecting rods 7 of a greater length than is the usual practice, or the cylinder of a greater diameter with the usual piston stroke;—all of which will be hereinafter considered and besides these changes, I make 50 the following addition.

Between each set of intake and exhaust chambers I form a discharge chamber 20 which communicates with the chamber 9 so as to receive an explosive mixture from 55 the cylinder 5, when the valves 10 and 11 are closed. The chamber 20 also communicates with an auxiliary manifold 21 suitably connected to the cylinders 5 and having a branch 22 communicating with the 60 main intake manifold 16, adjacent the carbureter 18. The manifold may be in the form of a nozzle 23 approximately in the plane of fuel emitted by the carbureter and constructively arranged to emit its fuel upwardly into the main intake manifold 16,

so that the initial charge of fuel may commingle with the secondary charge and the two charges enter the cylinders of the engine as the intake valves 10 are opened.

Each of the discharge chambers 20 is provided with a valve 24 opening into the chamber 9, said valve having a rod 25 extending through the chamber 20 in parallelism with the valve rods 12, so as to be operated from the cam shaft 13 similar to said valve rods 12, but in a different timed order relative thereto.

Considering the operation in connection with one cylinder with the piston 6 on the downstroke and the intake valve 10 open, 80 an explosive charge is drawn from the main intake manifold 16 through the chambers 14 and 9 into the cylinder 5, and bearing in mind that this cylinder has been redesigned or enlarged, approximately a greater 85 volume of fuel is drawn into the cylinder than is the usual practice. All of this fuel is to be heated by contact with the walls of the cylinder and on the up or compression stroke of the piston 6 the intake valve 10 is closed, and the excess discharge valve 24 90 opened for the first portion of the up or compression stroke of the piston. It is preferably the first part of the upward or compression stroke of the piston 6 that the excess discharge valve 24 is open so that some 95 of the heated explosive mixture will be returned to the chamber 9, pass through the chamber 20 into the auxiliary manifold 21, and through the branch 22 into the main 100 intake manifold 16, where it commingles with the initial supply of fuel and may enter one of the other cylinders of the engine.

As the piston 6 completes the first portion 105 of its upward or compression stroke the valve 24 is closed, so that approximately the usual volume of fuel will be retained in the cylinder 5 to be compressed therein and exploded. Assuming that the explosive mixture has been detonated, the piston 6 is forced downwardly on an impulse or work stroke and assuming that the cylinder is of greater length than usual, it is obvious that 110 the exploded mixture has greater opportunity to expand and perform work before the exhaust valve 11 is opened for a final atmospheric exhaust. It is therefore possible to derive a greater amount of energy 115 from the burned and expended gases and permit such gases to exhaust at a pressure approximating atmospheric pressure, and thus reduce the noise that accompanies the 120 usual exhaust of an engine.

In utilizing the heat of combustion as a 125 heating medium for an explosive mixture, it is obvious that the explosive mixture fed to all of the cylinders of the engine will be in better condition for the combustion, and this together with a change in the stroke 130

of the engine piston materially increases the efficiency of the engine as a power plant.

This phase of my invention may be more clearly understood by reference to Fig. 3. 5 In this figure of the drawings, the cylinder 5 has been increased in its diameter compared to the diameter of an ordinary cylinder, and in consequence of such increase there is necessarily a volumetric or gas capacity increase in the cylinder. It is therefore apparent that the large cylinder may receive a greater or excess charge of an explosive mixture, and, before such charge can be compressed to the same degree as the 10 charge in the usual size of cylinder, that the piston in the large cylinder must travel a greater distance, due to the ratio of clearance space to the piston displacement. For instance, in Fig. 3, I show by dot and dash 15 lines the position the piston may assume when it actually starts to compress and meets with the same resistance as in an ordinary cylinder. It will be noted that the piston has made a greater stroke than an ordinary piston 20 for the reason that it has not met with a compression resistance as high in the large cylinder. In other words, at the beginning of the stroke of the large piston there is practically no resistance, other than that 25 of moving a volume of gas, to be considered excess, and it is this excess volume that is expelled from the large cylinder, while the valve 24 is open, to commingle with a 30 fresh or initial charge and enter some other cylinder of the engine or be reserved for future use. So, since there is no actual compression to be accomplished by the large piston until it makes a greater stroke than an ordinary piston, it is obvious that the crank 35 6^a moving the large piston assumes altogether a different position, at the beginning of actual compression, than the crank of an ordinary piston. This difference of angularity has been brought out in Fig. 3 and it 40 is now evident that there is comparatively less torque and actual work to be performed by the crank shaft when the piston is completing compression. This may be considered in another way. For instance, it may 45 be said that during actual compression of an ordinary piston, the crank 6^a travels in an 50

arc one hundred and eighty degrees, whereas the crank of the large piston travels, for the same purpose, in an arc less than one hundred and eighty degrees, for instance, 55 during the lesser part of the crank ascension, or between two hundred and seventy and three hundred and sixty degrees of one revolution of the crank shaft.

It is obvious that when the length of the 60 cylinder is increased and also the connecting rods serving the pistons in said cylinders, that there is a change in the angularity of the connecting rods relative to the crank shaft during the operation of the piston that is different from that of ordinary connecting rods, and by providing long strokes there is less side thrust on the bearings of the crank shaft, less racking of the 65 engine and consequently greater efficiency. 70

It is thought that the operation and utility of my invention will be apparent without further description and while in the drawing there is illustrated a preferred embodiment of my invention, it is to be understood that the structural elements are susceptible to such changes, in size, shape and manner of assemblage, as fall within the 75 scope of the appended claim.

What I claim is:—

In an internal combustion engine, the combination with cylinders, an intake manifold therefor, and intake and exhaust valves controlling the admission of fuel to said cylinders from said intake manifold and the 80 exhaust of burned gases from said cylinders, of an auxiliary manifold establishing communication between said cylinders and said intake manifold, said engine cylinders being proportioned to receive a greater quantity of fuel than usual so that the excess quantity of fuel may be heated and expelled 85 from the cylinders to the intake manifold, and means controlling the expellation of the 90 excessive fuel from said cylinders. 95

In testimony whereof I affix my signature in the presence of two witnesses.

GEORGE D. HOWE.
